DINNER PLATE OR SIMILAR ARTICLE

Douglas Bourne, Falls Creek, Pa., assignor to The Jackson Vitrified China Company, Pelham Manor, N. Y., a corporation of Delaware

Application May 15, 1956, Serial No. 41,502

Term of patent 14 years

(Cl. D44—15)

The figure is a plan view of a dinner plate of conventional configuration showing my new design.

The plate to which the design is applied is conventional in shape.

The dominant feature of the design resides in the graded coloration toward the rim of the inner band and outer scalloped band.

I claim:

The ornamental design for a dinner plate or similar article, substantially as shown and described.
